(57) **CLAIM**

The ornamental design for a water bottle cap, as shown and described.

DESCRIPTION

FIG. 1 is a top perspective view of a water bottle cap, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the water bottle cap in an opened state;

FIG. 10 is a rear perspective view showing the water bottle cap in an opened state;

FIG. 11 is a front perspective view showing the water bottle cap in a fully opened state; and,

FIG. 12 is a rear perspective view showing the water bottle cap in a fully opened state.

The broken lines in the drawings illustrate the portions of the water bottle cap, which form no part of the claimed design.

1 Claim, 12 Drawing Sheets
